DISPLAY CARTON

Henry R. Goebel, Daly City, and George R. Karr, El Sobrante, Calif., assignors to Container Corporation of America, Chicago, Ill., a corporation of Delaware

Application January 16, 1952, Serial No. 266,708

4 Claims. (Cl. 229—36)

This invention relates to containers or cartons, and has to do more particularly with paper board cartons provided with openings or windows for display of the contents thereof.

Our invention is directed to the provision of a paper board display carton formed from a one-piece blank of paper board and which may be produced at comparatively low cost. The carton of our invention is of generally box-like formation with a cover having an opening and a transparent closure therefor providing a window for display of the contents of the carton. The end walls of the carton comprise interlocked end panels and are inclined or sloped upwardly and rearwardly of the carton for a substantial portion of their width, the cover having an inclined portion seating on the inclined portions of the end walls, for more effective display of the contents of the carton. We provide novel means for retaining the end panels of the carton interlocked and for retaining the inclined portion of the cover seated, when the cover is in its normal closed position. The cover also includes an upper or top portion which seats on the upper edges of the remaining uninclined portions of the end walls. We provide lock flaps cooperating with the top portion of the cover and with elements of the end wall panels and of the inclined or sloping portion of the cover, effective for retaining the end panels in interlocking engagement and for retaining the lower or inclined portion of the cover seated. In one form of our invention the back wall of the carton is also inclined, to more effectively display the contents thereof, as will be explained later. The carton of our invention is particularly suitable for containing and displaying doughnuts and will be shown and described as used for that purpose, though in its broader aspects it may be used for various purposes. A further feature of importance of our invention is the provision of air flow openings permitting free circulation of air through the carton and about the contents thereof. That is of particular importance in respect to glazed doughnuts which, if enclosed within a container without provision for free circulation of air, are apt to sweat with resultant melting or flowing of the glaze thereof, thus detracting from their appearance and saleability. The wall panels of the carton of our invention are connected together along fold lines and selected ones of the fold lines are serrated for portions thereof thus providing air flow openings located at or adjacent the bottom of the carton, as well as openings located a substantial distance above the bottom, whereby free circulation of air through the carton is assured. Further, by serrating portions of the fold lines, bending of the paper board about those fold lines is facilitated so that setting up of the carton is expedited. Further objects and advantages of our invention will appear from the detail description.

In the drawings:

Figure 1 is a plan view of a blank from which the carton of our invention is produced;

Figure 2 is an end view, on an enlarged scale, of the carton in partially set-up condition, showing the step of inserting the retaining tongue of one of the end wall panels through the slit in another end wall panel;

Figure 3 is an end view of the carton, on the same scale as Figure 2, illustrating the step of inserting the cover retaining flap through the slit in one of the end wall panels;

Figure 4 is a plan view of the carton in its fully set-up and closed condition, with the cover partly broken away and in section;

Figure 5 is a sectional view taken substantially on line 5—5 of Figure 4;

Figure 6 is a front view of the carton of Figure 4, fully closed and loaded with doughnuts;

Figure 7 is a plan view of a blank for producing a modified form of a carton embodying our invention; and

Figure 8 is an end view, on an enlarged scale, of the carton produced from the blank of Figure 7, with the cover closed.

- 10 The carton shown in Figures 2 to 6, inclusive, is produced from the blank of Figure 1. That blank is a single piece blank cut from a sheet of paper board and is suitably cut and scored to provide a bottom wall panel 10, a back wall panel 11 attached along a fold line to the back edge of panel 10, a front wall panel 12 of materially less height than the panel 11 and a cover 13 hinged to the upper edge of the front wall panel 12 along a fold line. The cover 13 comprises a lower panel 14, an upper panel 15 hinged along a fold line to the upper edge of panel 14, and a tuck flap 16 hinged to the rearward edge of the upper cover panel 15. The panel 15 is disposed at the top of the completely set up and closed carton and may be referred to as the top panel. The cover 13 is provided with an opening 17 of substantial area over which is secured a sheet 18 of cellophane or other suitable transparent material, providing a window through which the doughnuts or contents of the carton are readily visible. The tuck flap 16 is notched out at each end to provide tabs 20 at the ends of panel 15 and is also provided with a central notch 21 of considerable extent extending from its outer or lower end; the purpose of which will be described more fully presently. In the above description the various elements of the blank have been described with reference to the positions which they occupy in the completely set up carton, and the remaining elements of the blank will also be described in like manner, with a view to avoiding confusion.
- 20 The back wall panel 11 has attached to each end thereof, along a fold line, an inner end wall panel 29 having an upwardly and rearwardly inclined upper edge 22. A lock flap 23 is attached along a fold line to the upper edge of panel 29, flap 23 being notched out at its rearward edge to provide a locking tab 24. The panel 29 is provided with an upwardly extending slit 25 and the lock flap 23 is provided with a slit 26 constituting an extension of the slit 25. The back wall panel 11 is also provided, at its mid-length, with two parallel slits extending a short distance downward from its upper edge defining a tongue 27, which cooperates with the portion of the tuck flap 16 above notch 21 thereof for holding the tuck flap 16 in its inserted position in the carton, as will be explained more fully later. The bottom wall panel 10 is provided, at each end thereof, with an interior end wall panel 28 attached thereto along a fold line. Outer end wall panels 30 are attached to the ends of the front wall panel 12, along fold lines, the panels 30 having a maximum height approximately the same as the height of the back wall panel 11 and the inner end wall panels 29. Each of the panels 30 is provided, for a portion of its width, with an upwardly and rearwardly inclined upper edge 31 of approximately the same width or extent from front to back of the carton as the width of the lower panel 14 of cover 13. Each of the panels 30 is further provided, at the upper rearward portion thereof, with a retaining tongue 32 defining with the rearward edge of panel 30 a downwardly opening notch 33, from the upper end of which extends a short arcuate slit 34. Retaining flaps 35 are attached to the ends of the lower cover panel 14, along fold lines, the upper and the lower edges of the flaps 35 being parallel with the inclined upper edge 31 of the outer end panels 30. Portions of the fold lines between the bottom wall panel 10 and the back and front wall panels 11 and 12, and between the panels 11 and 29 and 10 and 28, are serrated at 36. The serrated areas 36 of the fold lines provide air flow openings when the blank is folded into carton form, as will be explained more fully later.
- 30 In order to produce the carton from the blank of Figure 1, the interior end wall panels 28 are folded upward into positions perpendicular to the bottom wall panel 10, the back wall panel 11 is folded upward into

position perpendicular to the bottom wall panel 10, and the inner end wall panels 29 are then folded forward at right angles to the back wall panel 11 extending forwardly therefrom in overlapping relation to the panels 28. The outer end wall panels 30 and the retaining flaps 35 are then folded into position extending rearwardly from the front wall panel 12 and the lower cover panel 14, respectively, and the front wall panel 12 is then swung rearward so as to insert the lower portions of the retaining tongues 32 through the slits 25 of the inner end wall panels 29 as in Figure 2. At that time, the lock flaps 23 are in vertical position providing upward extensions of the panels 29. The front wall panel 12 is then swung rearward into position seating on the front edges of the interior panels 28, thereby fully inserting the retaining tongues 32 through the slits 25, the upper portions of the tongues 32 also passing through the slits 26 of the lock flaps 23. The inner and outer end wall panels 29 and 30 are then interlocked, as in Figure 3, and provide, together with the interior end panels 28, the end walls of the carton. The cover 13 is then swung rearward about its hinge or fold line connection to the upper edge of the front wall panel 12, with the retaining flaps 35 inserted between the upper portions of the inner and outer end wall panels 29 and 30. In this rearward swinging movement of the cover, the retaining flaps 35 enter the slits 25 and also pass through the slits 26, the lock flaps 23 remaining in their vertical position shown in Figure 3. The rearward swinging movement of cover 13 continues until panel 14 thereof seats on the upwardly and rearwardly inclined edges 31 of the outer end panels 30, at which time the retaining flaps 35 have been fully inserted through the slits 25, as permitted by the slits 26, and are then positioned at the inner faces of panels 30, and, at their rearward portion, at the inner faces of the panels 29. The upper edges of the retaining tongues 32 and of the retaining flaps 35 are then approximately flush with the upper edges of the rearward portions of the panels 29 and 30, as in Figure 5.

As will be noted from Figures 3 and 5, the retaining tongues 32 and the retaining flaps 35, when fully inserted through the slits 25 as above described, extend a substantial distance rearward beyond slits 25 and beyond the forward edges of the lock flaps 23. The lock flaps 23 are then folded downward and inward into position extending inward from the end walls of the carton and overlying the tongues 32 and flaps 35, restraining them against withdrawal and locking the end wall assemblies together. The doughnuts or other articles may then be placed within the carton, after which the top panel 15 of cover 13 is swung downward so as to seat on the upper edges of the end walls, the tuck flap 16 being inserted downwardly between the lock flaps 35 and the upper portion of the back wall panel 11, with the tongue 27 at the inner face of the portion of the tuck flap 16 above the notch 21. Tongue 27 is then sprung inward to a certain extent and causes bulging outward to a slight extent, in notch 21, of the corresponding area of tuck flap 16, effective for retaining the cover in closed position. As the top panel 15 of cover 13 is pressed downward into its fully seated position, the tabs 24 spring upward into the notches provided by the tabs 20 so as to overlie the end portions of the upper edge of the tuck flap 16, providing means supplementary to the tongue 27 for holding the cover closed. Obviously, if desired, in placing articles, such as doughnuts, within the carton, the doughnuts may be placed inside of the carton after the retaining tongues 32 have been fully inserted through the slits 25, the cover 13 being swung forward about its hinged connection to the upper edge of the front wall panel 12 so as to provide an unobstructed opening for placing of the doughnuts in the carton. Thereafter, the retaining flaps 35 are inserted through slits 25, the locking flaps 23 are folded downward and inward and the cover is fully closed in the manner above described. It will be seen that in the fully closed position of cover 13, top panel 15 thereof retains the lock flaps 23 in their folded locking condition and cooperates therewith for retaining the end wall panels 29 and 30 locked together and also retaining the lower cover panel 14 seated on the inclined upper edge portions of the end walls. The window in the cover is thus inclined for the major portion of its width so as

to display to best advantage the contents of the carton, as will be clearly seen from Figure 6.

The serrated portions of the fold lines between the panels of the carton provide, in the set up carton, openings 37 at the ends and the front and back of the bottom thereof, and openings 38 at the ends of the back above the bottom wall. The openings 37 and 38 permit free circulation of air through the carton effective for preventing sweating of glazed doughnuts or other articles within the carton. The serrations 36 also facilitate folding of the panels of the blank into their proper positions in setting up the carton.

The blank of Figure 7 is substantially the same as the blank of Figure 1 and the various elements of the blank of Figure 7 have been indicated by the same reference numbers, with the exponent *a* added, as the corresponding elements in Figure 1. The blank of Figure 7 is set up in the same manner as the blank of Figure 1, to produce the carton shown in Figure 8. This carton is substantially the same as the carton shown in Figures 2 to 6, inclusive, except that in Figure 8 the back wall panel 11a is inclined upward and rearward and the top panel 15a of the cover 13a is appreciably wider than the top panel 15 of the cover 13 in Figures 2 to 6, inclusive. Inclining the back wall panel 11a upwardly and rearwardly increases the interior width of the carton, which is well suited for receiving larger or over-sized doughnuts. With the exceptions above noted, the carton of Figure 8, and the blank of Figure 7 from which that carton is produced, are substantially the same as the blank and the carton of Figures 1 to 6, inclusive, and further description thereof is not necessary.

We claim:

1. In a paper board display carton, a box-like body comprising a bottom wall panel and front and back wall panels connected at their lower edges to said bottom wall panel along fold lines, end walls respectively comprising an end wall panel extending forwardly from said back wall panel and an end wall panel extending rearwardly from said front wall panel, the latter being of materially less height than said back wall panel and said end wall panels being of substantially greater height than said front wall panel, the upper edges of said end wall panels being inclined for a portion of the width thereof upwardly and rearwardly from said front wall panel, the respective back wall end wall panels having an upwardly extending slit therein and said front wall end wall panels having rearwardly extending and downwardly directed retaining tongues extending through and below said slits, a cover comprising a lower panel hinged to the upper edge of said front wall panel and seating on the inclined portions of the upper edges of said end wall panels and a top panel hinged to the upper edge of said lower panel, lock flaps hinged to the remaining portions of the upper edges of said back wall end wall panels and folded into locking position extending inward therefrom, said lock flaps being provided with slits constituting extensions of said back wall end wall panel slits, and retaining flaps extending from the ends of said lower panel rearwardly through said back wall end wall panel slits, said lock flaps overlying said retaining flaps and said tongues and restraining them against upward movement, said top panel seating on the upper faces of said lock flaps and retaining them in locking position.
2. In a paper board display carton, a box-like body comprising a bottom wall panel and front and back wall panels connected at their lower edges to said bottom wall panel along fold lines, end walls respectively comprising an end wall panel extending forwardly from said back wall panel and an end wall panel extending rearwardly from said front wall panel, the latter being of materially less height than said back wall panel and said end wall panels being of substantially greater height than said front wall panel, the upper edges of said end wall panels being inclined for a portion of the width thereof upwardly and rearwardly from said front wall panel, said front wall end wall panels having retaining elements downwardly engageable with and upwardly disengageable from said back wall end wall panels for holding said end wall panels together, a cover comprising a lower panel hinged to the upper edge of said front wall panel and seating on the inclined portions of the upper edges of said end wall panels and a top panel hinged to the upper edge of said lower panel, lock flaps hinged to the upper edge of said back wall panel and retaining flaps extending from the ends of said lower panel rearwardly through said back wall end wall panel slits, said lock flaps overlying said retaining flaps and said tongues and restraining them against upward movement, said top panel seating on the upper faces of said lock flaps and retaining them in locking position.

wall panels and folded into locking position extending inward therefrom, and retaining flaps extending rearward from the ends of said lower cover panel, said lock flaps overlying said retaining flaps and said retaining elements and restraining them against upward movement, said top panel seating on the upper faces of said lock flaps and retaining them in locking position.

3. In a paper board display carton, a box-like body comprising front and back wall panels, inner end wall panels extending forwardly from the ends of said back wall panel and respectively provided with upwardly extending slits, outer end wall panels extending rearwardly from the ends of said front wall panel and provided with retaining tongues extending through and downwardly beyond said slits, said front wall panel being of materially less height than said back wall panel and said inner and outer end wall panels overlapping at their inner portions and together constituting end walls, the upper edges of said end wall panels being inclined for a portion of the width thereof upwardly and rearwardly from the upper edge of said front wall panel, a cover comprising a lower panel hinged to the upper edge of said front wall panel and seating on the inclined upper edge portions of said end wall panels and a top panel hinged to the upper edge of said lower panel, retaining flaps extending from the ends of said lower cover panel rearward between said end wall panels and through said slits, and lock flaps hinged to the remaining portions of the upper edges of said inner end wall panels and provided with slits constituting extensions of the slits in said inner end wall panels, said lock flaps being folded into locking position extending inward from said inner end wall panels and overlying said tongues and retaining flaps, said top panel seating on the upper faces of said lock flaps and retaining them in locking position.

4. In a paper board display carton, a box-like body comprising a bottom wall panel, an upwardly and rear-

wardly inclined back wall panel attached at its lower edge to said bottom wall panel along a fold line, a front wall panel of materially less height than said back wall panel attached at its lower edge to said bottom wall panel along a fold line, inner end wall panels extending forwardly from the ends of said back wall panel and respectively provided with upwardly extending slits, outer end wall panels extending rearwardly from the ends of said front wall panel and provided with retaining tongues extending through and downwardly beyond said slits, said inner and outer end wall panels overlapping at their inner portions and together constituting end walls, the upper edges of said end wall panels being inclined for a portion of the width thereof upwardly and rearwardly from said front wall panel, a cover comprising a lower panel hinged to the upper edge of said front wall panel and seating on the inclined upper edge portions of said end wall panels and a top panel hinged to the upper edge of said lower panel, retaining flaps extending from the ends of said lower cover panel rearward between said end wall panels and through said slits, and lock flaps hinged to the remaining portions of the upper edges of said inner end wall panels and provided with slits constituting extensions of the slits in said inner end wall panels, said lock flaps being folded into locking position extending inward from said inner end wall panels and overlying said tongues and retaining flaps, said top panel seating on the upper faces of said lock flaps and retaining them in locking position.
